US00D894794S

(12) **United States Design Patent** (10) **Patent No.:** **US D894,794 S**
Virgo et al. (45) **Date of Patent:** **** Sep. 1, 2020**

(54) **MOBILITY AID**

(71) Applicants: **Carolyn Virgo**, Los Angeles, CA (US); **Steven Montgomery**, Los Angeles, CA (US); **Robert Shuman**, Granada Hills, CA (US)

(72) Inventors: **Carolyn Virgo**, Los Angeles, CA (US); **Steven Montgomery**, Los Angeles, CA (US); **Robert Shuman**, Granada Hills, CA (US)

(**) Term: **15 Years**

(21) Appl. No.: **29/734,707**

(22) Filed: **May 14, 2020**

(57) **CLAIM**

The ornamental design for a mobility aid, as shown and described.

DESCRIPTION

FIG. 1 is a perspective view embodying the inventive design;

FIG. 2 is a rear view thereof;

FIG. 3 is a right side view thereof;

FIG. 4 is a left side thereof;

FIG. 5 is a front view thereof;

FIG. 6 is a top view thereof; and,

FIG. 7 is another perspective view thereof, showing the design in its collapsed, portable state.

The broken lines are directed to environment and form no part of the claimed design.

1 Claim, 7 Drawing Sheets
